R. J. PANZER
INVENTOR

BY Victor J. Evans

ATTORNEY

UNITED STATES PATENT OFFICE.

ROBERT JOSEPH PANZER, OF SUMMIT, ILLINOIS.

CONTAINER.

Application filed February 18, 1925. Serial No. 10,135.

This invention relates to new and useful improvements in containers and more particularly to a device especially adapted for use in containing articles of jewelry and the like. The main object of the present invention is the provision of a container divided into several compartments whereby various articles of jewelry are contained within the compartments so that they may 10 be quickly and readily obtained when it is desired to use the same.

Another object of my invention is the provision of a container which will be preferably known as a handy companion with the body of the container having a removable tray divided into several compartments for receiving various articles of jewelry and the like and suitable space being provided between the bottom of the container and the 20 removable tray whereby handkerchiefs, neckties and small articles of apparel may be readily carried within the container.

With the above and other objects in view, my invention consists in the novel features 25 of construction and the combination and arrangement of parts to be hereinafter more fully described, pointed out in the claim and shown in the accompanying drawings, in which:

30 Fig. 1 is a perspective view of a container constructed in accordance with my invention.

Fig. 2 is a transverse sectional view with the cover in an open position, and

35 Fig. 3 is a transverse section through the casing adjacent one end thereof with the tray removed.

In carrying out my invention I provide a substantially rectangular body member 1, 40 although, various other designs may be used in forming the container. Hinged to one side of the body 1 is a cover 2 having downwardly projecting flanges 3 around the edges thereof.

45 Arranged within the body and extending longitudinally thereof upon each side wall is a supporting flange 4 which supports the removable tray 5. This tray 5 is divided into several compartments by means of the transverse and longitudinal extending strips 6 and 7, forming a central transverse compartment 8, and upon opposite sides of the central transverse compartment are the transversely aligned compartments 9 extending longitudinally of the case, thus forming 55 at least five compartments in the tray.

The compartments of the tray 5 are normally closed by means of an inner cover member 10 which consists of a stiff body portion 11 having a covering of leather, 60 velour or other similar material with the cover portion extending beyond the inner longitudinal edge of the body 11 and secured to the inner side of the rear wall of the body 1, as shown at 12, whereby to provide a 65 hinged connection between the inner cover 10 and the rear side of the body 1. The forward edge of the cover 10 is provided with a fastening member 13 adapted to engage a fastening member 14 carried by the 70 inwardly projecting ear 15 on the tray whereby the cover 10 may be securely retained in position over the upper face of the tray. In order to facilitate raising of the cover 10 a flexible loop 16 is connected to 75 the upper surface thereof adjacent the forward edge, as is clearly illustrated in Figure 2.

The cover 2 carries a hasp 17 at its outer edge adapted to engage with a lock member 80 18 carried by the body whereby to securely retain the cover 2 in a closed position. The interior of the cover is preferably covered with a mirror 19 and the cover is supported in a raised position as shown in Figure 2 85 by means of the bars 20 which are pivotally connected to the end flanges of the cover as at 21 while the lower ends carry pins 22 which are movable in the slots 23 formed upon the inner faces of the end walls of the 90 body 1, said slots having a downturned portion 24 in which the pins 22 rest when the cover is in a raised position.

It will be noted that by supporting the tray 5 in spaced relation with the bottom 95 of the body 1, a compartment 25 is provided beneath the tray whereby handkerchiefs, neckties, socks and small articles of apparel of this character may be carried within the container. The upper face of the tray 5 is 100 preferably covered with a soft pliable covering; such as, velour, plush or the like, as shown at 26, so as to provide convenient nesting for valuable articles of jewelry.

From the above description taken in connection with the accompanying drawings, it will be readily appreciated that a container constructed in accordance with my invention will be extremely useful for the traveling public, due to the fact that this container may be made up in various designs and shapes for carrying various articles of 105 110

jewelry and small articles of wearing apparel so that they need not be placed in a travelling bag or other container in a loose state, and when placed in my improved container will be always in position so as they may be readily obtained for use.

While I have shown and described the preferred form of my invention, it will be obvious that various changes in the details 10 of construction and in the proportions may be resorted to for successfully carrying my invention into practice without sacrificing any of the novel features or departing from the scope of the appended claim.

Having thus described my invention, 15 what I claim is:

An article of the class described including a body, a removable tray defining a number

of compartments and confined within the body in spaced relation with respect to the bottom wall of the body and including an inwardly projecting portion formed on one of the side walls of the tray, means for supporting the tray in said spaced relation, a cover member hingedly connected to the body 25 for the tray, a flexible loop connected to the cover member to facilitate moving the cover member from closed position with respect to the tray, fastening members carried by the cover member and the projecting portion 30 for releasably holding the cover member in closed position with respect to the tray, and a closure lid for the body.

In testimony whereof I affix my signature.

ROBERT JOSEPH PANZER.
